UNITED STATES PATENT OFFICE.

JOHN W. BIRDSEYE, OF GORHAM, NEW YORK.

GRAB FOR PUMP-RODS AND PIPES.

1,148,495.

Specification of Letters Patent.

Patented Aug. 3, 1915.

Application filed February 23, 1915. Serial No. 9,925.

To all whom it may concern:

Be it known that I, JOHN W. BIRDSEYE, a citizen of the United States, residing at Gorham, in the county of Ontario and State of New York, have invented certain new and useful Improvements in Grabs for Pump-Rods and Pipes, of which the following is a specification.

The object of this invention is to provide a new and improved form of device that will permit the recovery of a lost pipe and pump rods in so-called driven wells. This and other objects of the invention will be fully illustrated in the drawings, described in the specification and pointed out in the claims at the end thereof.

In the drawings, Figure 1 is a vertical section of the well casing with the lost pipe and pump rod therein showing my apparatus in use for the purpose of recovering it. Fig. 2 is a large detail view of my improved device with a modification embodied therein. Fig. 3 is a detail view of the nipple that forms part of my apparatus. Fig. 4 is a detail view of the device shown in Fig. 2, shown with the grab adapted to be used in connection therewith.

In the drawings like reference numerals indicate like parts.

Reference numeral 1 indicates the well casing such as is used in driven or bored wells, which wells frequently extend to a depth of several hundred feet.

2 indicates the water pipe and 3 the pump rod which is generally used to connect the pump that is always used at the bottom of a well with a handle for operating the pump at the top of the well. In this case the pipe and pump rod are shown as they frequently appear lost in a well casing.

It will be understood that the water pipe is usually about $1\frac{1}{2}$ " in diameter and the well casing is ordinarily 5" or 6" in diameter, although the dimensions are immaterial for the purposes of my invention. It will also be understood that the sucker rod is usually about $\frac{1}{2}$ " in diameter.

After the boring of the well is finished it is customary to lower the pump with a section of the pipe and the sucker rod into the well casing. An additional section of water pipe and sucker rod is then coupled on and the pump is lowered still further. In like manner additional sections of pipe and sucker rod are connected until the pump rests in its proper position at the bottom of

the well and the water pipe and sucker rod are exposed at the top of the well for the purpose of being connected to the pump and fittings. It sometimes happens, however, that after the pump and one or more sections of water pipe and sucker rod have been connected thereto they will get away and drop down into the well in which case the well is useless until the pipe and pump have been removed and my device has for its purpose the removal of the water pipe and sucker rod that have been lost under such circumstances.

Referring now to the drawings, reference numeral 2^A indicates a sleeve having a coupling 3^A at the outer end into which is secured a plug 4 to which is connected a rod or tube 5, which rod may be increased in length by the addition of sections according to the depth to which the device must be lowered into the well. To the bottom of the sleeve 2^A is connected a coupling 6 having a cone shaped hood 7 fastened thereon projecting downwardly therefrom. This cone shaped hood 7 is adjustable or expandable to fit the various dimensions of well casings in connection with which it is used and for this purpose is divided along the line 8 indicated in Fig. 2, the outer section having a series of holes therein which may be made to register with any of the three series of holes 9, 9 shown in Fig. 2, two layers of metal being fastened together by bolts or any other suitable device.

Inside of the cone shaped hood 7 is fastened the deflecting device 10, the upper end of which is slotted as indicated at 11 between upwardly and inwardly inclined fingers 12. In use this apparatus is lowered into the well casing until it comes into contact with the pump rod and pipe which it will then encircle, passing down around it and deflecting it to the middle of the casing until the pipe passes between the fingers 12 with the pump rod 3 extending up into the sleeve 2^A. The water pipe will then be in position to be engaged with the nipples 13 or 14. The nipple 14 is used where the pipe has a female thread at the top, the nipple being tapered so that it will enter the opening at the top of the pipe. If, however, the pipe has a male thread at the top, the nipple 13 will be substituted for the nipple 14. The nipple 13 is provided with a female thread which tapers, expanding toward the bottom so that it can envelop the top of the pipe and make en-

gagement therewith. In either case the pump rod will pass up through the nipple 13 or 14 and into the sleeve 2^A. The rod or pipe 5 by which the apparatus is manipulated from the top of the well is rigid with the device so that the device can be turned thereby and make threaded engagement. If, however, the well is too deep to permit of the use of the rigid connection 5 the connection 5 and plug 4 will be omitted and the apparatus will be handled otherwise by a device which I will now describe.

The sleeve 2^A is slotted at three places opposite each other at 120 degrees apart, which 15 slots are fitted with the dogs 17. Inside of the sleeve is provided a grab 18 which consists of a tube having a plug 19 at the top thereof, in which is fastened a bar 15 having an eye 16 at the top thereof. The grab 18 is slotted suitably to receive the dogs 17 on the sleeve 2^A and below the grab 18 are the flat spring strips 20, preferably three in number, having the jaws 21, 21 at the bottom thereof, which jaws will normally stand just 25 above the fingers 12. When the parts are assembled the dogs 17 will engage in the slots in the tube of the grab 18, the sleeve 2^A being thereby suspended from the grab 18 (see Fig. 4). With the parts in this relation a rope will be attached to the eye 16 and the apparatus will be lowered to any desirable depth. When it comes into engagement with the water pipe and pump rod the pipe and pump rod will be deflected into 35 engagement with the jaws 21, the apparatus being lowered until the water pipe comes into contact with the dogs 17 and as it is further lowered the dogs will be spread until they are forced out of engagement with the 40 grab 18, after which the sleeve 2^A can drop, causing the tapered portion at the bottom of the coupling 6 to engage with the dogs 21 and force them together against the pipe and clutch it. The grab and water pipe can then

be raised by the rope to the top of the well 45 casing and removed.

I claim.

1. In a device of the character described the combination of a sleeve, a coupling attached having a female thread therein, said coupling having a downwardly and outwardly flaring exterior, a cone shaped hood attached to said coupling and extending downwardly therefrom, a deflecting and centering device supported in said hood, said deflecting device having fingers therein that converge toward the opening in said coupling.

2. In a device of the character described the combination of a sleeve, a coupling attached having a female thread therein, said coupling having a downwardly and outwardly flaring exterior, a cone shaped hood attached to said coupling and extending downwardly therefrom, a deflecting and centering device supported in said hood, said deflecting device having fingers therein that converge toward the opening in said coupling, and a nipple fastened in said coupling adapted to engage with a pipe.

3. In a device of the character described the combination of an outer sleeve, dogs thereon, an inner sleeve having openings therein with which said dogs are adapted to engage for the purpose of supporting the outer sleeve, strips attached to said inner sleeve having jaws at the bottom thereof, said inner sleeve and jaws being adapted to embrace a pipe and permit said pipe to push said dogs out of engagement with the inner sleeve permitting the outer sleeve to drop and press said jaws inwardly.

In testimony whereof I affix my signature in presence of two witnesses.

JOHN W. BIRDSEYE.
